UNITED STATES PATENT OFFICE.

CLARENCE H. BRYAN, OF CHICAGO, ILLINOIS.

ALARM.

SPECIFICATION forming part of Letters Patent No. 670,702, dated March 26, 1901.

Application filed December 10, 1900. Serial No. 39,275. (No model.)

To all whom it may concern:

Be it known that I, CLARENCE H. BRYAN, a citizen of the United States, residing at Chicago, in the county of Cook and State of Illinois, have invented a certain new and useful Improvement in Alarms, of which the following is a specification.

My invention relates to a cheap, simple, and convenient device for giving the alarm when 10 a burglar is attempting to enter a house, or it may be used as an alarm for any other purpose or as a door-bell. It is illustrated in the accompanying drawings, wherein—

Figure 1 is an elevation showing one form 15 of my invention as applied to a door-knob. Fig. 2 is a side elevation of a different form of the device with the knob removed. Fig. 3 is a detail of a modification of the bell-wire.

Like parts are indicated by the same letter 20 in all the figures.

A is the door; B, the exterior knob; C, the interior knob; D, the spindle; E, the key-hole; F, the key therein; G, a wire or rod or spring. It may be straight, as shown, or 25 it may be spiral, as shown in G', Fig. 3, at one end of which is the alarm device (in this case a bell H) and at the other end a bent portion J, which surrounds the spindle. This bent portion is continued downwardly par- 30 allel with the wire G and is then bent into a horizontal loop K, which keeps the rod or wire G at a proper distance away from the door, so as to free the key and at the same time keep the alarm device or bell away from interfer- 35 ence with the door. The end K' overhangs or hooks onto the wire G, so that the device is firmly gripped upon the door-knob spindle.

In the modified form the rod or wire G is extended in the form of a spring L, so that 40 when once the bell has been disturbed it continues giving its alarm for a considerable period.

Many modifications could be made in the device without departing from the spirit of 45 my invention. It might be attached to the inner extremity of devices other than that shown, it only being necessary that the outer extension be such as would commonly be in- terfered with by the burglar. Moreover, it 50 might be attached to any device which, like

the knob and spindle, is loosely secured in the door, for in that case, even though not directly touched by the burglar, it would nevertheless give the alarm if the door were interfered with or caused to shake or rattle. 55 Again, the device may be attached in any manner to the projecting part. I do not therefore wish it to be limited to the particular form shown. It may be held under by the springing action of the rod or by the clamp- 60 ing action resulting from the end K' overhanging the rod or wire, or it may be held by screws or otherwise.

I have shown my attachment removably se- 65 cured to the spindle, as this is most convenient. The rod or wire is supposed to be made of spring metal, so that it will spring over the spindle, and thus the parts may be easily at- tached or disengaged. The loop K can be dispensed with, if desired, and this would be 70 proper under some conditions. The alarm device itself might be other than a mechanical alarm; but I prefer a simple mechanical alarm which responds to any shaking or rat- tling of either the door or the knob. 75

The use and operation of my invention are of course evident.

The burglar if he undertakes to enter through the door or in any manner interferes with the door will turn the knob or rattle the 80 door sufficiently to set the alarm-bell vibrat- ing, whereupon the inmates are advised of what is going on. In this case of course the noise is heard by the person interfering with the door, so that he is alarmed and driven 85 away many times when the bell may not have been heard by the inmates. Such portable alarms can be attached readily to any or all of the outside or inside doors of a house and can be carried about conveniently. They can be 90 attached to hotel door-knobs, and thus the oc- cupant of a separate room is given compara- tive security, as in such case frequently the only way to enter the room is through the door. Such a device can also be used to rouse 95 the sleeper when applied in country hotels, where no other means for that purpose are employed.

As previously explained, my device may be used as a burglar-alarm, or it may be used as 100

a hotel call-bell, or it may be used as a private door-bell, and can be applied and taken off from time to time when and as required.

I claim—

- 5 1. In an alarm for doors, the combination of a bell with a pendulum-like support therefor, means connected with said support whereby it may be removably attached to the spindle of the door-knob, and means located between the knob and the bell and connected with said support and projecting laterally to engage the door so as to keep the bell out of contact with the door, and the upper end of the support out of contact with the key.
- 10 2. In an alarm for doors, the combination of a bell with a pendulum-like support, provided with, first, a spring-clamping bend to
- 15

engage the spindle of the door-knob, second, a hook or catch to hold the parts together about the spindle, third, a laterally-projecting coiled portion to engage the door, said coiled portion located between the bell and the knob-spindle, and projecting so far toward the door as to keep the upper part of the support out of engagement with the key, and the bell out of engagement with the door, and a spring part associated with the support to keep the bell ringing after it has once been started. 20 25

CLARENCE H. BRYAN.
